A. E. AUGUSTINE,
TRAP MECHANISM FOR ENVELOPE MAKING MACHINES,
APPLICATION FILED SEPT. 20, 1919.

1,403,374.

Patented Jan. 10, 1922.

UNITED STATES PATENT OFFICE.

ADDISON E. AUGUSTINE, OF HACKENSACK, NEW JERSEY, ASSIGNOR TO CHESTER MACHINE CO., INC., OF NEW YORK, N. Y., A CORPORATION OF NEW YORK.

TRAP MECHANISM FOR ENVELOPE-MAKING MACHINES.

1,403,374.

Specification of Letters Patent. Patented Jan. 10, 1923.

Application filed September 20, 1919. Serial No. 325,109.

To all whom it may concern:

Be it known that I, ADDISON E. AUGUSTINE, residing at Hackensack, in the county of Bergen and State of New Jersey, have invented certain new and useful Improvements in Trap Mechanism for Envelope-Making Machines, of which the following is a specification.

This invention relates to trap mechanism for envelope-making machines.

The object of the invention is to provide improved and simplified means for adjusting the creasing ring of the trap relative to the remainder of the trap.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown merely a preferred form of embodiment of the invention—

Figure 1 is a top plan view of the trap constructed in accordance with this invention, portions being broken away for better illustrating the construction and arrangement of parts thereof.

Figure 2 is a longitudinal vertical sectional view taken substantially upon the plane of line II of Fig. 1.

Figure 3 is an end view of the trap shown in Fig. 1 showing the same mounted in position within the supporting table of the envelope-making machine, and

Figure 4 is a transverse vertical sectional view taken substantially upon the plane of line IV of Fig. 1.

Referring to the drawings for describing in detail the structure which is illustrated therein, the reference character L indicates the body portion of the trap while the reference character G indicates the creasing ring of the trap.

The body portion L may be formed in any suitable manner but is preferably formed as a single cast metal member provided with opposite end ears 1 by means of which it is pivotally connected with the table 2 by means

of the pivot shaft 3, the body being thus held to swing about the pivot for discharging the envelopes which are folded upon its upper surface, in the usual manner.

The body is also provided with bearing portions 4 at its opposite ends to which are pivotally connected the ends of operating links 5 by means of which the trap may be swung.

The body L is formed with a top wall 6 which provides a flat upper surface 7 upon which the envelope is folded, in the usual manner, as will be readily understood by those familiar with this class of device, said surface being apertured, if desired, as at 8, for the supply of suction power to hold the envelopes during the discharge operation, said apertures 8 being in communication with a passage 9 which is in turn connected with a suitable suction apparatus not shown.

The creasing ring G is formed entirely separate from the body and consists of a solid rectangular member telescoping slidably over the correspondingly shaped upper portion of the body so that the upper surface, as 10, of the ring may be moved more or less nearly into the plane of the surface 7, according to requirements.

The means whereby to adjust the position of the ring G constitutes the essential feature of this invention, and, as illustrated, consists of a pair of wedge rods 11 and 12, the rod 11 being positioned beneath the forward portion of the ring G and the rod 12 being positioned beneath the rear portion of the ring G. These rods rest upon smooth upper surface portions 13 formed upon the body L and their upper surfaces, which engage under surface portions of the ring G, are inclined or beveled, as at 14, so that the rods constitute in effect wedges adapted to move the ring upwardly as the rods are forced to a greater or less extent into position beneath the ring.

Suitable adjusting screws, as 15 and 16, are provided for moving the bars, or wedges, 11 and 12. These screws are each provided with an annular grooved portion 17 engaging within suitable openings 18 formed in a retaining plate 19 so that the screws are not permitted longitudinal movement but yet are free to rotate so that threaded portions, as 20, of the screws, which engage within threaded openings 21 of the bars,

will serve to move the bars in either direction according to the direction of rotation of the screws.

The retaining plate 19 is fixed rigidly at 5 the forward side of the trap, and the head ends 22 of the two screws project through this plate side by side so that they are both in position for easy and convenient manipulation at any time.

10 The screw 15 has no operative connection with the bar 11 at the forward side of the ring but extends loosely through openings 23, 24 and 25 formed through the bar 11 and through the forward and rear wall portions respectively of the body L and has its threaded portion 20 engaging the threaded opening 21 of the bar 12 at the rear of the trap so that this screw 15 is adapted only for adjusting the rear bar.

20 The screw 16 on the other hand has no connection with the bar 12. It is short and extends only through the plate 19 and directly into engagement with the threaded opening 21 of the bar 11 so that it is adapted only for adjusting the bar 11.

25 It will thus be seen that the bars 11 and 12 are adapted for independent adjustment so that either the forward or rear portions of the ring G may be vertically adjusted 30 without materially affecting the position of the opposite portion of the ring.

35 It is desirable under certain conditions to provide guide means for insuring uniform movement of the rods 11 and 12 throughout their length whenever the screws 15 or 16 are rotated. Any appropriate guide means may be utilized for this purpose but as a simple expedient the drawings herewith illustrate the bars 11 and 12 to be fitted with guide 40 members 26 and 27 respectively, the guide member 27 being tubular and the guide member 26 being slidably received within the guide member 27 so that each forms a guiding supporting for the other end yet 45 each may move independently of the other. Each guide member is, of course, fixed rigidly to its respective bar so that the bars must necessarily remain at all times parallel with each other.

50 Any suitable yielding retaining device may be employed for urging the ring G downwardly at all times so that it will properly cooperate with the bars 11 and 12. As an example of such means the drawings 55 illustrate four spring tension devices 28 one arranged adjacent each corner of the ring, in the usual manner.

60 It will be understood that in the operation of this device the envelope blank is 65 positioned upon the surface 7 of the trap, substantially in the position as indicated diagrammatically by the heavy line 29 in Fig. 3, and that the upstanding flaps of the envelope indicated by the vertical portions of the line 29, are then folded down substan-

tially in the position as indicated by the heavy dotted lines 30 in Fig. 3. The folding down of the flaps is accomplished by suitable folders not illustrated, and the degree of sharpness of the bends at the points 70 31 is dependent upon the nearness of register of the surface 10 of the ring with the surface 7 of the body. If these surfaces are in a common plane the bend at the points 31 will be very sharp, while when the surface 10 is below the plane of the surface 7 the bend will be less and less sharp as the surface 10 is adjusted more and more below the plane of the surface 7. Envelopes of 75 certain classes require sharper bends than others, sometimes because of the different texture of paper used and sometimes because of the likes and dislikes of the manufacturer. Also, envelopes of different styles will require more or less variation as between the bend at the forward side of the trap and the bend at the rear of the trap. These various requirements are simply and efficiently provided for by the means above described.

80 As many changes could be made in this construction without departing from the scope of the invention as defined in the following claims, it is intended that all matter contained in the above description, or shown 85 in the accompanying drawings, shall be interpreted as illustrative only and not in a limiting sense.

90 Having thus described my invention, what I claim as new and desire to secure by Letters Patent is:—

1. In a trap mechanism for envelope-making machines, the combination with a body member and a creasing ring carried thereby, of a pair of wedges arranged for engaging 105 different portions of the creasing ring, means to move said wedges for adjusting the position of the guide ring relative to the body member, and guide means for said wedges including a pair of interengaging 110 parts one carried by each wedge.

2. In a trap mechanism for envelope-making machines, the combination with a body member and a creasing ring carried thereby, of a pair of wedges arranged for engaging 115 different portions of the creasing ring, means to move said wedges for adjusting the position of the guide ring relative to the body member, and guide means for said wedges including a pair of telescopically engaging 120 parts one fixed to each of said wedges.

3. In a trap mechanism for envelope-making machines, the combination with a body member and a creasing ring carried thereby, of a pair of wedges disposed at opposite sides 125 of the creasing ring, and means at one side of the body by which from said mentioned side of the body to move both of said wedges independently of each other for adjusting the position of the ring.

4. In a trap mechanism for envelope-making machines, the combination with a body member and a creasing ring carried thereby, of a pair of wedges disposed at opposite sides 5 of the creasing ring, and a pair of screws having portions engaging the respective wedges and having other portions terminating at one side of the body whereby to adjust both of said wedges from the same side 10 of the body.

5. In a trap mechanism for envelope-making machines, the combination with a body member and a creasing ring carried thereby, of a pair of wedges disposed at opposite 15 sides of the creasing ring adjustable for altering the position of the creasing ring relatively to the body, a screw extending from one side of the trap loosely through one of said bars and into engagement with 20 the other bar, whereby to adjust said other bar, and a second screw extending from the same side of the trap into engagement with the first bar whereby to adjust the first bar.

6. In a trap mechanism for envelope-making machines, the combination with a body member and a creasing ring carried thereby, of a pair of wedges disposed at opposite 25 sides of the creasing ring adjustable for altering the position of the creasing ring 30 relatively to the body, a screw extending from one side of the trap loosely through one of said bars and into engagement with the other bar whereby to adjust said other bar, the intermediate portion of said screw extending through an opening provided 35 through the body, and a second screw ex-

tending from the same side of the trap into engagement with the first bar whereby to adjust the first bar.

7. In a trap mechanism for envelope-making machines, the combination with a body member and a creasing ring carried thereby, of a pair of separately formed wedges disposed at opposite sides of the creasing ring, means whereby said wedges are supported 45 to slide from one position to another with respect to the creasing ring, and means at one side of the body by which from said mentioned side to move said wedges independently of each other for adjusting the 50 position of the creasing ring.

8. In a trap mechanism for envelope-making machines, the combination with a body member and a creasing ring carried thereby, of a pair of separately formed wedge bars 55 extending in substantially parallel relation to each other along opposite sides of the body and having their wedge surfaces constantly engaging the creasing ring, means whereby said wedge bars are supported to 60 slide bodily toward and away from each other, and means at one side of the body by which from said mentioned side to move said wedge bars independently of each other for adjusting the position of the creasing ring. 65

In testimony whereof I affix my signature in the presence of two witnesses.

ADDISON E. AUGUSTINE.
